UNITED STATES PATENT OFFICE.

FRANK DUTCHER, OF VERSAILLES, PENNSYLVANIA, ASSIGNOR TO AMERICAN FOG SIGNAL COMPANY, OF PITTSBURG, PENNSYLVANIA.

RAILWAY SIGNAL-FUSE.

No. 853,777.

Specification of Letters Patent.

Patented May 14, 1907.

Application filed June 17, 1905. Serial No. 265,798.

To all whom it may concern:

Be it known that I, FRANK DUTCHER, a citizen of the United States, residing at Versailles, in the county of Allegheny and State 5 of Pennsylvania, have invented certain new and useful Improvements in Railway Signal-Fuses, of which the following is a specification, reference being had therein to the accompanying drawings.

10 This invention relates to improvements in railroad signal fuses, and pertains to certain improvements in covers for igniting material of railway signal fuses.

15 Referring now to the drawings, Figure 1, is a side elevation of a torch showing my improved cover applied thereto in section. Fig. 2, is a similar view showing a modified construction of plug for the outer end of the cover. Fig. 3, is a detached perspective view 20 showing a preferred form of my improved auxiliary cap. Fig. 4, is a detached perspective view of the plug illustrated in Fig. 1. Fig. 5, is a similar view of the plug illustrated in Fig. 2.

25 The usual form of torch 1 is used, which has at its upper end the usual igniting member 2. Applied to the igniting end of the torch 1 is a tubular cover 3 which serves to cover and protect the igniting member or 30 material 2 of the torch. Thus far, I have described the usual construction of torch and cover for the exposed igniting member thereof.

35 I will now refer to the features which constitute my present invention.

In carrying out my present improvement, the plug 4, which closes the outer end of the tubular cover 3, is provided with a suitable shoulder 5. In Fig. 1 this shoulder 5 is provided by extending the plug outward, into an annular flange as shown in Fig. 4, the annular flange extending beyond the periphery of the tubular cover 3. In Fig. 2, the annular shoulder 5 is provided by forming a groove 6 in the plug, the plug being of substantially the same diameter as the external diameter of the tubular cover 3.

40 My improved auxiliary cap is constructed to co-act with the plug 4, so that when placed in position, as shown in Figs. 1 and 2, it is held there against accidental removal or displacement, for the purpose of protecting the complementary igniting material 7 which is on the outer end of the plug 4, and is

adapted to co-act with the igniting member 55 or material 2 of the torch proper, in a manner which is well understood by those skilled in the art, and does not need further description herein.

As shown, the auxiliary cap 8 and the plug 60 4 are constructed to interlock with each other, and this may be accomplished in many ways. The preferred form is that here shown, and it consists, as shown clearly in Fig. 3, in providing the cup-shaped auxiliary 65 cap 8 with depending ears or projections 8', which are adapted to be bent inward under the shoulder 5 of the plug 4, and thus will hold it in position.

The cap 8 is preferably formed of metal, 70 and usually tin, being made from scrap tin preferably, for the purpose of cheapness in construction.

I am aware that metal caps for hermetically sealing bottles of a construction somewhat similar to the protecting cap herein shown, have been used. These differ essentially from my invention, in that the sealing caps for bottles are tightly clamped in position, and must be so to effect the sealing 75 thereof, and that because of this tight clamping of the sealing cap, it is necessary in some forms to use a specially constructed tool in order to remove the sealing cap, or to construct the sealing cap in such a way that it 80 can be broken away, which, however, is not practical to do with the fingers, because they are so tightly clamped in order to accomplish their function. My cap is a quick-removing cap, which is not tightly clamped in 85 position, so as to require either a special tool or a breaking away of the holding ears. To the contrary, the ears are only loosely bent inward sufficiently to hold the protecting cap by friction, and which can be quickly removed by an endwise pull upon the cap. The tightly clamped sealing caps for bottles 90 would absolutely defeat the object of applicant's invention. The object is to merely protect the igniting material in such a way 95 that it can be quickly and readily exposed for use in emergencies, without requiring either a special tool, or the equally tedious method of segregating the parts of the cap.

To facilitate the application of the auxiliary cap to the end of the plug, the latter is 100 preferably provided with an inclined annular surface 9 which enables the cap to be forced

thereon, even should the ears of the cap be bent slightly inward.

While I have here shown a specific and preferred form of the auxiliary protecting cap or cover, and of the plug 4, whereby the two interlock, I desire it to be understood that variations in the precise manner here shown may be made, without departing from the spirit and scope of my invention.

Having thus described my invention, what I claim and desire to secure by Letters Patent, is:—

An improved cover for fuses comprising a tubular member, a plug closing one end there-

of and having its outer end provided with a complementary igniting material and with a lateral shoulder, and a quick removable cup-shaped metal cap having downwardly-projecting members loosely and frictionally engaging the said shoulder, whereby it can be removed with the fingers by an endwise pull thereon, substantially as described.

In testimony whereof I affix my signature in presence of two witnesses.

FRANK DUTCHER.
